UNITED STATES PATENT OFFICE.

ALBERT COWELL, OF KIDDERMINSTER, ENGLAND.

DESIGN FOR A CARPET-PATTERN.

Specification forming part of Design No. 5,717, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new design of the borders of rectangular figures formed on a carpet, which borders are shown in the photograph; also, to a new design for the borders

of the carpet itself, which consists of a succession of symmetrical scrolls, as shown.

A carpet of the general design shown is especially adapted as a stair-carpet, for use in halls and wherever single strips are required, though it is also suitable as a regular floor covering.

I claim as my invention—

The design for the carpet containing the ornamental borders and figures, as shown.

ALBERT COWELL.
